UNITED STATES PATENT OFFICE.

WILLIAM H. JAMOUNEAU, OF NEWARK, ASSIGNOR TO THE ALVIN MANUFACTURING COMPANY, OF JERSEY CITY, NEW JERSEY.

DESIGN FOR A SILVERSMITH'S STOCK.

SPECIFICATION forming part of Design No. 25,286, dated March 24, 1896.

Application filed February 21, 1896. Serial No. 580,267. Term of patent 7 years.

To all whom it may concern:

Be it known that I, WILLIAM H. JAMOUNEAU, a citizen of the United States, residing in Newark, in the county of Essex and State 5 of New Jersey, have invented and produced a new and original Design for Silversmiths' Stocks, of which the following is a specification, reference being had to the accompanying drawings, in which—

10 Figure 1 is a plan view, and Fig. 2 a sectional view thereof.

The leading feature of my design consists of a shell-like center bearing a shield and having two curved arms radiating from opposite sides thereof, the latter being pro-

vided with a series of beads intercepted by a leaf.

A is the shell-like center decorated and having the contour, as shown, the central field thereof bearing the shield B. From the center radiate the two curved arms C, each of which is decorated with a row or series of beads D and leaf E, all as shown.

What I claim is—

The design for silversmiths' stocks substantially as herein shown and described.

WILLIAM H. JAMOUNEAU.
